UNITED STATES PATENT OFFICE.

SAMUEL WEISS, OF NEW YORK, N. Y., ASSIGNOR TO LEHMAN BROTHERS SILVERWARE CORPORATION, OF NEW YORK, N. Y., A CORPORATION OF NEW YORK.

DESIGN FOR AN URN OR SIMILAR ARTICLE.

Application filed May 12, 1926. Serial No. 17,673. Term of patent 3½ years.

To all whom it may concern:

Be it known that I, SAMUEL WEISS, a citizen of Russia, but has applied for naturalization papers in the United States, residing in the borough of Manhattan, city of New York, county of New York, and State of New York, have invented a new, original, and ornamental Design for an Urn or Similar Article, of which the following is a specification, reference being had to the accompanying drawings, forming a part thereof.

Fig. 1 is a front view of an urn or similar article showing my new design.

Fig. 2 is a side view of the same.

I claim:—

The ornamental design for an urn or similar article, as shown.

SAMUEL WEISS.
